UNITED STATES PATENT OFFICE.

FREDRIQUE R. LEWIS, OF WORCESTER, MASSACHUSETTS, ASSIGNOR TO
WOOD & LEWIS, OF TROY, NEW YORK.

DESIGN FOR A CUFF.

SPECIFICATION forming part of Design No. 20,634, dated March 24, 1891.

Application filed February 25, 1891. Serial No. 382,828. Term of patent 3½ years.

To all whom it may concern:

Be it known that I, FREDRIQUE R. LEWIS, a citizen of the United States, residing at Worcester, county of Worcester, and State of Massachusetts, have invented and produced a new and original Design for Cuffs, of which the following is a specification, reference being had to the accompanying drawing, forming a part thereof, and consisting of a single figure showing in plan a cuff detached and laid out flat.

The leading feature of my new design consists in the bifurcate form of the ends of the cuff. Each end of the cuff is provided with

a gore-shaped opening A, located midway of the parallel edges B B, forming the bifurcate arms C C, of equal width. Each of the bifurcations is provided with a button-hole D.

What I claim as new, and desire to secure by Letters Patent, is—

The design for a detachable cuff herein shown and described.

In testimony whereof I have hereunto set my hand this 20th day of February, 1891.

FREDRIQUE R. LEWIS.
